United States Patent Office

Des. 195,961

Patented Aug. 13, 1963

195,961

MICROPHONE

Raymond Spilman, Darien, Conn., assignor to The Astatic Corporation, Conneaut, Ohio, a corporation of Ohio

Filed May 28, 1962, Ser. No. 70,299

Term of patent 7 years

(Cl. D26—14)

FIG 2

FIG 1

FIG 3

FIG 4

FIGURE 1 is a perspective view of a microphone embodying my new design.

FIGURE 2 is a front elevational view of the microphone shown in FIGURE 1.

FIGURE 3 is a side elevational view of the microphone shown in FIGURE 1; and

FIGURE 4 is a rear elevational view of the microphone shown in FIGURE 1.

I claim:

The ornamental design for a microphone, as shown.
